UNITED STATES PATENT OFFICE.

CHARLES ROBERTSON, OF SEATTLE, WASHINGTON.

CAN-FILLING APPARATUS.

1,096,953.

Specification of Letters Patent. Patented May 19, 1914.

Application filed January 3, 1911. Serial No. 600,660.

To all whom it may concern:

Be it known that I, CHARLES ROBERTSON, a citizen of the United States of America, and a resident of the city of Seattle, county 5 of King, and State of Washington, have invented certain new and useful Improvements in Can-Filling Apparatus, of which the following is a specification.

The present invention pertains to an im- 10 proved machine of the above type especially designed for filling cans with fish meat.

The primary object of the invention is to provide a machine capable of feeding 15 different supplies of meat separately, assembling and molding with one supply such portion of the other supply as may be required to complete a filling, and transferring the molded filling to a can.

20 The invention is further directed to the provision of automatic mechanism for cutting fish bodies transversely into sections or "steaks," placing within each section a filling portion, compressing the filled section and transferring the same to a can.

With the above and other objects referred 25 to hereafter in view the invention consists in certain novel features and combinations of parts as set forth in the specification and 30 defined in the annexed claims.

In the accompanying drawings, wherein similar reference characters designate corresponding parts throughout the several views: Figure 1 is a sectional plan of a 35 can filling machine embodying the features of my invention in such form as now preferred by me, portions of some of the parts being broken away and the carrier and molding device shown in their right hand 40 terminal positions. Fig. 2 is a side elevation of the machine with the upper parts in section on line 2--2 of Fig. 1 and portions of some of the lower parts broken away. Fig. 3 is a fragmentary side elevation. Fig. 4 is a horizontal section on line 4--4 of Fig. 2. Fig. 5 is a fragmentary plan in partial section with the molding device in its left hand terminal position. Fig. 6 is a fragmentary section on line 6--6 of 45 Fig. 1. Fig. 7 is a plan of the molding device and cutter frame removed, the latter being shown in partial section, and Fig. 8 is a fragmentary perspective of the carrier and secondary feeding device together with

one of the primary feeding devices and its cutter.

The machine herein disclosed embodies in its molding device and secondary feeding mechanism certain novel features claimed in my application Serial No. 518,095, filed 5 Sept. 18, 1909, as will be understood upon comparing the said application with the present.

The main frame 1, as shown, embodies vertically spaced, horizontal plates 2, 3 provided with aligned apertures 2', 3' and connected with face plates 4, 4 fitting against the outer face of a curved frame 5 which is mounted, concentric with a vertical rock shaft 6, in slide ways 2'', 3'' of the plates, 70 2, 3 and provided at its inner side with a vertical cross plate 5' constituting a cutter. Between the plates 2, 3 is a molding device comprising a segmental slide block 7 having peripheral recesses 7', 7' and provided 75 with an intermediate compression part 9 projecting between opposite compression parts 9', 9' constituting rim sections of a segmental slide frame 8 which is movable endwise on block 7 and fits against the inner face of frame 5.

At the outer side of the molding device is a horizontal supply carrier 10 having spaced feeding passages 10', 10' whose inner side walls 11 extend to the path of cutter plate 5' while their outer side walls 11' extend rearwardly concentric with a rotary fork support 12 and constitute the inner side walls of feeding channels 13, 13. Communicating with the channels 13, 13 are vertical feed ways 14, 14 which are each adapted to receive a fish body prepared as will be presently described, for endwise projection into the underlying channel 13. These feed ways are each provided with a 85 longitudinally extending tongue 14a of suitable form to serve as a spreader in the fish body to hold the side walls thereof apart and thereby guide the body in proper form to the forwarding means as will be later 90 understood.

15, 15 designate cutters movable beneath the feed ways 14, 14 for severing sections of "steaks" from fish bodies and conveniently consisting of circular blades secured to vertical arbors 16, 16 journaled on opposite arms 17 fixed to a loose adjusting sleeve 18 which is mounted in a vertical sleeve 19

journaled on a bracket hanger 20 of carrier 10. Secured to the arbors 16, 16 are spur gears 21, 21 connected by intermediate gears 21', 21' with a spur gear 22 fixed to the 5 sleeve 19 which is provided at its lower end with a driving wheel in the form of a sprocket 20'.

For forwarding body sections or steaks in the channels 13, 13, I have shown horizontally disposed U-shaped members or forms 23, 23 which normally lie directly beneath the tongues 14^a, 14^a and have connection with independent arms 24, 24 fixed to respective loose sleeves 25 nested with the 10 sleeves 18, 19 on a shaft 26 and provided each with a fixed adjusting wheel 25' in form of a sprocket. Each form 23, as 15 shown, has curved stems 23' which extend rearwardly at opposite sides of the path of 20 the adjacent arbor 16 and are secured to a vertical extension 24' of the underlying arm 24.

Support 12 comprises segmental rim sections spaced to provide passageways at opposite sides of the support for a double ended fork 27 and connected with a hub 12' which is fixed to shaft 26 and provided with a transverse guide way wherein fork 27 is slidably mounted for projections of its 30 end portions alternately from the support.

In the present construction of carrier 10 the side walls of the passages 10' and channels 13 are connected with a segmental bottom plate 10^a while the walls of the feed 35 ways 14, 14 have connection with respective top plate sections 10^b, 10^b secured to the side walls 11, 11 and lying above the paths of the cutter 15, 15. Plate 10^a extends into curved end guides 10^c which are engaged in 40 suitable slide ways provided on arm extensions 3^a of plate 3.

The mold block 7, as shown, is provided with a radial arm 6' which is fixed to shaft 6 for intermittent reciprocatory movement 45 of the block to present the recesses 7' alternately in line with the aperture 2', 3', while the frames 5, 8 are secured, respectively, to fixed arms 5'', 8'' of loose sleeves 50, 80 which are nested with shaft 6 and provided 50 at their lower ends with fixed arms 51, 81 respectively. See Fig. 2. In this connection it will be observed that shaft 6 is mounted in a step bearing 30' of a rectangular part 30 of frame 1 while sleeve 50 is journaled in plate 3 which is secured to a vertical extension 30'' of part 30.

Journaled on frame part 30 is a rotatable cam 31 connected by differential spur gearing 32 with a shaft 33 for rotation at a 60 five ratio of one half revolution to one. Shaft 33 is provided with a driving pulley 34 for continuous rotation and connected by miter gears 35 with a vertical shaft 36 which is rotatably supported with shaft 33 on an 65 angle bracket 33' of part 30. Shaft 36 ex-

tends through a journal aperture in plate 3 and carries a fixed cam 37 provided with a cam groove 37' engaging a suitable follower on a lever 38 which is pivoted as at 38', on plate 3 and connected by a link 39 with the 70 adjacent guide 10^c of carrier 10. Groove 37' is formed with opposite throw sections extending eccentrically to shaft 36, for reciprocating carrier 10 through the medium of lever 38 and link 39, and intermediate connecting sections extending concentrically with said shaft to provide for terminal pauses in the movements of the carrier. Mold block 7 has a movement similar to that of carrier 10 imparted from cam 31 through 75 the medium of a cam groove 7' which engages a suitable follower on a fixed arm 60 of shaft 6. This groove is suitably designed to move block 7 in a previous manner relatively to carrier 10 with terminal pauses 80 during each of which one recess 7' is discharged and the other filled. In the filling operation a section or steak is first placed in a recess 7' with the carrier in an opposite terminal position relatively to the mold 85 block, as for example, as shown in Fig. 5, the carrier is then moved to its opposite terminal position and the secondary filling mechanism operated to fill the body section 90 or steak as will be later understood. Frame 95 8 is moved during terminal pauses of block 7 to apply the retracted compression member 9' and then advanced in common time with the block to reverse position. Frame 5 is moved during initial movements of frame 8, 100 but in a reverse direction relatively to the frame to carry cutter plate 5' between the filled recess 7' and its related passage 10'. The movement of frame 8, which as will be understood from the foregoing is an intermittent reciprocatory movement, is effected 105 by a suitable cam groove 8^a of cam 31 acting on a follower of a lever 82 which is pivoted to an extension of bracket 33' and connected by a link with arm 81 of sleeve 80. Frame 110 5 is operated by similar mechanism including a suitable cam groove 5^a provided in cam 31 and engaging a follower on a lever 52 which is pivoted alongside lever 82 and connected by a link with arm 51 of sleeve 50. Fork 27 is conveniently shifted on hub 12' by movement of carrier 10 through the medium of a lever 27^a pivoted at 27' to the carrier and having slotted connection with a stationary bearing in pin 27'' on plate 2, 115 and a link 27^b connected with said fork and the lever. During movement of the carrier from either of its terminal positions to the other, lever 27^a bears against pin 27'' and is thereby adjusted on its fulcrum to shift fork 27 in the direction the carrier is moving to an opposite position relatively to support 12. This adjustment of the fork positions it for a feeding operation which is effected 120 during terminal pause of the carrier with 130

block 7 by an angular movement of support 12 in a manner to be now described.

Secured to shaft 26 of support 12 is a sprocket 26' having link belt connection 5 with a sprocket 26'' secured to a loose sleeve 26^a which is provided with an arm 71 and nested with loose sleeves 24^a, 24^b and 17^a on sleeve 50. Arm 71 has link connection with a lever 72 which is pivoted to a bracket 33'' 10 of frame part 30 and provided with a suitable follower engaging in a cam groove 12^a of cam 31. This groove is suitably designed to move lever 72 when carrier 10 is resting in either of its terminal positions and effect 15 through medium of the connecting mechanism just described, proper angular movement of support 12 to advance the projected end of fork 27 for feeding. The cutters 15 are advanced alternately by angular reverse 20 movements of sleeve 18, which is provided with a sprocket 18' having link belting connection with a sprocket 18'' secured to sleeve 17^a. Sleeve 18 and support 12 are turned simultaneously but in relatively reverse 25 directions, so that the cutter 15 at the inactive end of the carrier, as for example, the one on the left in Fig. 1, is advanced for cutting as support 12 is turned to force filling from the passage 10' at the opposite or active end 30 of the carrier. Cam 31' is provided with a cam groove 15^a of suitable design to effect the above described advance movements of the cutters 15 through the medium of a follower lever 74 which has link connection 35 with an arm 75 of sleeve 17^a and is pivoted to an extension of bracket 33'.

20'' indicates a double sprocket wheel rotatably mounted on sleeve 50 for continuous operation from the driving mechanism, not shown, and connected by link belting with sprocket 20' of the driving mechanism of the cutters 15.

Each arm 24 is reciprocated in an independent manner with respect to the other arm to advance and retract its form 23 while the adjacent cutter 15 is in its advanced position. In this connection it will be observed that the sprockets 25' of the arms 24 are connected by link belts with respective 45 fixed sprockets 25'' of the sleeves 24^a. The inner sleeve 24^a is therefore connected with the outer one of the sleeve 25 which carries the arm 24 on the left in Fig. 1, while the other sleeve 24^a is connected with the sleeve 25 which carries the right hand arm 24. The sleeves 24^a have independent connection with cam 31, as will be later understood, whereby form 23 on the left in Fig. 1 is advanced to feed a body section or steak to the left hand recess 7', following movement 50 of mold block 7 to its left terminal position, as indicated in Fig. 5, and then retracted, and form 23 on the right operated in a similar manner with respect to the right hand recess 7' when carrier 10 and mold block 7

are respectively in their left and right hand terminal positions.

23^L, 23^R indicate cam grooves of cam 31 engaging, respectively, with follower levers 76, 77 which are pivoted on bracket 33'' and 70 have link connection with arms 76', 77' fixed, respectively, to the inner and outer companion sleeves 24^a. These grooves 23^L, 23^R, which as will be understood from the foregoing have connection with the left and 75 right hand arms 24 respectively, are suitably designed to effect intermittent operation of the arms 24 in an alternating manner and in proper time relatively to movements of carrier 10, mold block 7 and cutters 80 15 to reciprocate the left form 23 when its cutter 15 is in advanced position, as shown in Fig. 1, but with the mold block set to the left, as in Fig. 5, and to reciprocate the right hand form 23 when its cutter 15 is in advanced position with carrier 10 shifted to the left and the mold block in its right hand terminal position.

40 indicates a rotatable support provided with opposite can seats 41 and having a vertical bearing stem 42 which is slidable in a journal bracket 43 of plate 3 and combined with intermittently operated turning and elevating mechanism whereby the seats 41 are presented alternately beneath opening 3' 90 and the support elevated and lowered each time a seat is presented. The turning mechanism comprises a segmental gear 44 meshing with a pinion 44' fixed on stem 42 and journaled on a bracket 46 of frame part 30 95 in rigid connection with an arm 47 which has link connection with a lever 47 pivoted to a bracket 46'' and provided with a follower engaging a cam groove 40^a of cam 31. The elevating mechanism comprises companion thrust cams 48, 48' loosely mounted on an extension 42' of stem 42 and provided with opposing, inclined end surfaces. Cam 48' has an angular body extension slidably engaged in a corresponding aperture in 105 bracket 46 in opposing relation to the hub of pinion 44', while cam 48 is supported on a step extension 46' of said bracket and provided with a rigid arm 49 having a follower engaging in a cam groove 40^b of cam 31. 110 Cam groove 40^a is suitably designed to reciprocate lever 47 with terminal pauses occurring with those of the mold block 7, while groove 40^b is designated to effect during each pause of lever 47 a reciprocation of arm 49 115 with a pause at the end of its forward stroke to hold support 40 in elevated position during the passage of filling to a can, as will be now described.

Fitting freely in opening 2' of plate 2 is 125 a plunger 54 having an angular stem 54' which is slidably engaged in a vertical guide way on a standard 55 of plate 3 and has a pin and slot connection with a vertically movable swing arm 56 fixed to a cross pin 130

56" journaled in said standard. Secured to the opposite end of pin 56" is an outwardly extending arm 56' having a follower engaging in a peripheral cam groove 57' of a cam 57 which is secured to shaft 36. Groove 57' is suitably designed to effect an upward and downward movement of arm 56 during each pause of the mold block 7 with the downward movements of the arm 10 occurring in time with the forward strokes of arm 49 of thrust cam 48 and to thereby advance plunger 54, through the medium of arm 56, to press filling from the molding device through opening 3' when support 40 15 is elevated.

Opening 3' communicates with a counterbore provided in an annular flange 3^b of plate 3 to receive the rim of the can and flared at its lower edge to provide a surface 20 for guiding the can into the flange. The seats 41 are each provided with a marginal, semicircular guard flange 41' and opposite resilient arms 41" between which arms the can to be filled is pressed to position it against the guard flange during 25 intermission in the rotary movement of support 40.

The fish bodies are placed in the feed ways 14 minus their tail and shoulder portions, which portions, previously cut off, are thrown into the passage ways 10' to be forwarded by fork 27, as a filling for the body sections severed by the cutters 15, and forwarded under action of the forms 23 to the 30 molding device as previously described. The bodies placed in the feed ways 14 gravitate when the respective cutters 15 are retracted following the forwarding of the body sections severed by the advance movements of these cutters, as will be readily 35 understood.

With the machine parts in the relative positions shown in Figs. 1 and 5 and assuming that the left hand mold recess 7' has 40 been charged with filling and support 40 is moving under action of cam 31 in the direction of the arrow, in Fig. 4 with a can to be filled positioned, as at C, a continued operation of the machine would be as follows: The frames 8, 5 move simultaneously in opposite directions responsive to action of the cam grooves 8^a, 5^a and apply, respectively, the retracted compression part 9' and cutter plate 5', as heretofore described. Mold block 7 then moves in common time 45 with frame 8 under a throw action of cam groove 7^a which brings the right hand recess 7' beneath plunger 54 and the left hand recess 7' opposite its feeding channel 13, as indicated in Fig. 5. In the meantime the relative throw action of cam groove 40^a has continued the rotation of support 40 one quarter of a turn bringing can C beneath opening 3'. A throw of cam groove 23^a 50 now effects a forward movement of the left

hand form 23 which advances a body section or steak, previously severed by the adjacent cutter 15, into the left hand recess 7', while a throw of groove 40^b effects an angular movement of thrust cam 48, which 55 elevates support 40 and thereby applies the rim of can C in flange 3^b. Cam 57, in the meantime effects a downward movement of plunger 54 and continues such movement after application of the can in flange 3^b to 60 advance the plunger through the underlying recess 7' into the opening 3' and thereby force the filling into the can. While plunger 54 is being advanced form 23 is retracted by a reverse throw action of groove 23^b, and a throw section of cam 37 moves carrier 10 to its left hand terminal position. This movement of the carrier effects, through 65 medium of lever 27^a, a movement of fork 27 to the left on support 12 and brings the left hand passage 10' opposite the left hand recess 7' into which a body section or steak has just been placed. Support 12 and the adjusting sleeve 18 of the cutter arms 17 are now turned in relatively opposite directions by single throw actions of the grooves 70 12^a, and 15^a, respectively, of cam 31, groove 12^a effecting a movement of support 12 which advances fork 27 to fill the body section or steak, while groove 15^a effects a turning 95 movement of sleeve 18 which advances the right hand cutter 15 and retracts the left. In the meantime a return movement of plunger 54 has been effected by action of its cam, and the thrust cam 48 reversed, by action of a return throw of groove 40^b, allowing support 40 to come by gravity to a lowered position. The support is now reversing under action of a return throw of groove 40^b with a second can, placed manually on 100 the opposite seat 41, to position it for filling while returning the can just filled. Carrier 10, mold block 7 and frame 8 are now in their left hand terminal positions and frame 5 in its right hand terminal position, while 105 the cutters 15 are in relatively reversed positions and support 12 in reversed angular position with respect to the showing in Fig. 1. The return operation of the frames 8, 5 and mold block 7 is effected by return throws 110 of their respective grooves in cam 31 to first compress the body section or steak in the left hand recess 7' with its filling and sever this filling from the supply and then return frame 8 and block 7 in common time to present the filled recess to plunger 54. The right hand form 23 is then advanced and retracted by reverse throw actions of groove 23^b and carrier 10 returned by a reverse 115 throw action of cam 37 thereby causing a projection of fork 27, by reverse action of lever 27^a, to the right of support 12. The support is then turned by a reversed throw action of groove 12^a and sleeve 18 simultaneously turned by a reverse throw action 120 125 130

of groove 15^a whereby support 12 and cutters 15 are returned to the positions shown in Fig. 1. The second can in the meantime has been brought forward, elevated in flange 5 3^b and lowered, by succeeding throw sections of the grooves 40^a, 40^b effecting movements of support 40 as before, and the plunger again lowered and raised by a succeeding throw section of its cam.

10 Having thus described my invention, what I claim as new, and desire to secure by Letters Patent of the United States of America, is:

1. In can filling apparatus, separate material feeding devices, means whereby material from one of said devices is assembled with that discharged from the other, and means for pressing and then holding pressed and simultaneously transferring the assembled supply.

15 2. In can filling apparatus, separate material feeding devices, means receiving material discharging from both of said feeding devices, and means for compressing the assembled supply in said first means and then holding such material pressed and simultaneously advancing the same.

20 3. In can filling apparatus, a movably supported mold formed of sections one of which is movable to compress the material, separate feeding means movably supported for feeding to said mold at a common point, means for closing said mold, and means for moving said mold with its pressed assembled supply.

25 4. In can filling apparatus, separate feeding means, a mold supported for movement to receive material from each of said feeding means, an ejector, and means for reciprocating said mold to advance the same to said ejector during one stroke.

30 5. In can filling apparatus, separate feeding means, a mold supported for movement to receive material from each of said feeding means, an ejector, and means for compressing the assembled material in said mold and then holding the same pressed and simultaneously advancing the same to said ejector.

35 6. In can filling apparatus, separate feeding means, a mold having a movable compression member, means for operating said feeding means to alternately advance material to said mold, an ejector for said mold, means for operating said compression member to its pressing position, and means for advancing said mold with its said compression member to said ejector.

40 7. In can filling apparatus, separate feeding means, a mold supported for movement, means for moving said mold to present the same alternately to said feeding means, and means for operating said feeding means alternately.

45 8. In can filling apparatus, separate feed-

ing means and an assembling means, one of which is movable relatively to the other, means for operating said feeding means alternately to forward material to said assembling means, means for pressing the material assembled in said assembling means, an ejector, and means for shifting said assembling means to said ejector while the product is held pressed by said pressing means.

50 9. In can filling apparatus, a supply means having a feed channel, an assembling means positioned to receive material from the feed channel of said supply means, a form device supported for movement to hold material to hollow form and advance the same to said assembling means, and means for depositing other material within that material advanced by said form device.

55 10. In can filling apparatus, a supply means provided with feed channels, and an assembling means, one of which is relatively movable, whereby said assembling means can receive material from the feed channels of said supply means alternately, means for discharging material from one of the feed channels of said supply means and holding said material in hollow form, and means for discharging material from the other of said feed channels into the hollow body of material inserted into the assembling means by said first named discharging means.

60 11. In can filling apparatus, a supply carrier provided with communicating angularly disposed feed passages, and a cutter supported for movement across the path of material forwarded through one of said feed passages to the other.

65 12. In can filling apparatus, a supply carrier provided with communicating angularly disposed feed passages, a cutter, means on which said cutter is journaled supporting the same for movement across the path of material forwarded through one of said feed passages to the other, and means for driving said cutter.

70 13. In can filling apparatus, a supply carrier provided with communicating feed passages, one of which extends upwardly from the other, a cutter supported for movement across the path of material forwarded through the last named of said feed passages, and means operating in the other of said feed passages for forwarding the charges severed by said cutter.

75 14. In can filling apparatus, a supply carrier provided with communicating angularly disposed feed passages, a cutter supported for movement across the path of material forwarded through one of said feed passages, said last named feed passage being provided with a spreading device for holding the walls of a fish body apart during

- feeding movement of the latter to said cutter, and a form device operating in the other of said feed passages to engage in the steaks received from said cutter and forward the same. 5
15. In can filling apparatus, a supply carrier provided with a feed channel, form means operating in said feed channel to advance material while holding the same in a predetermined hollow condition, a movably supported assembling device receiving material from said form means, other feeding means operating to place a filling within the material forwarded to said assembling device by said form means, and means whereby the product is ejected from said assembling device. 10
16. In can filling apparatus, a reciprocating supply carrier provided with a plurality of feed channels, means for discharging material from said feed channels alternately upon respective movements of said carrier, and an assembling means receiving the material as discharged from both of the feed channels of said carrier. 15
17. In can filling apparatus, a reciprocating supply carrier provided with a plurality of feed channels, means for discharging material from said feed channels alternately, an assembling means arranged for reception of the material discharged from said feed channels, an ejector, and means for moving said assembling means with its product to said ejector. 20
18. In can filling apparatus, a reciprocating supply carrier having a feed channel, a support mounted on said carrier for relative movement, a feeding device mounted on said support for alternate projection into and retraction from said feed channel, means for operating said support to move said device for feeding, and means whereby said feeding device is alternately projected and retracted by movement of said carrier. 25
19. In can filling apparatus, a reciprocating supply carrier having a feed channel, a support rotatably mounted on said carrier, means for operating said support, and a feeding device mounted on said support for movement into and out of said feed channel operated by and during movement of said carrier. 30
20. In can filling apparatus, a reciprocating supply carrier having spaced feed channels, a rotatable support mounted on said carrier, opposed feeding devices mounted on said support for alternate projection into and retraction from respective feed channels of said carrier, means for operating said support for alternately moving said feeding devices through their respective feed channels, and means whereby each feeding device is alternately projected and retracted by movement of said carrier. 35
21. In can filling apparatus, means for feeding material, a molding device comprising a member supported for movement and provided with a recess adapted to receive material from said means, a compression member supported for independent movement from one side wall of said recess toward the opposite side wall thereof, and means for operating said compression member to press the material in the recess of said molding device. 40
22. In can filling apparatus, means for feeding material, a molding device comprising a slidably supported member formed with a material receiving recess having relatively long and short opposing walls, and an independently movable compression member operating over the shorter wall of said recess and opposing the longer wall thereof. 45
23. In can filling apparatus, means for feeding material, a molding device comprising a slidably supported member formed with a material receiving recess having relatively long and short opposing walls, an independently movable compression member movable into said material receiving recess from over the said short wall thereof, and a cutter operating between said means and said molding device. 50
24. In can filling apparatus, means for feeding material, a molding device supported for movement and provided with a material receiving recess, a compression member forming a portion of one wall of said recess and being movable relatively to the remaining portion of said wall, a cutter operating between said means and said molding device, and means for operating said cutter and said compression member in relatively opposite directions. 55
25. In can filling apparatus, a molding device comprising a member supported for movement, said member being formed with a plurality of material receiving recesses, and movably supported compression members each mounted for movement beyond adjacent walls of respective material receiving recesses and into the latter. 60
26. In can filling apparatus, a molding device comprising a member supported for movement, said member being formed with a plurality of material receiving recesses, and compression members forming portions of adjacent walls of respective recesses of said device and relatively movable for projection beyond the same into the said recesses. 65
27. In can filling apparatus, a molding device comprising a member supported for movement and formed with a plurality of material receiving recesses, compression members each associated with a respective recess of said device and constituting a portion of one side wall thereof, and means connecting said compression members for si- 70

multaneous movement, one being operated to a compressing position while the other is moved to a relatively reverse position.

28. In can filling apparatus, a supply means having two sets of feed passages, a molding device having material receiving recesses each related to a respective set of feed channels of said supply means, and means whereby material is fed into the said recesses of said molding device alternately from the feed channels of their respective sets.

29. In can filling apparatus, a reciprocating supply means having two sets of feed passages, a relatively movable molding device having material receiving recesses each arranged for reception of material from a respective set of said feed passages, means for advancing material through said sets of feed passages operating to discharge material alternately from the passages of a set, and means for compressing the material in the recesses of said molding device.

30. In can filling apparatus, a reciprocating supply means having two sets of feed passages, a relatively movable molding

device having material receiving recesses each arranged for reception of material from a respective set of said feed passages, means for advancing material through said sets of feed passages operating to discharge material alternately from the passages of a set, means for compressing the material in the recesses of said molding device, an ejecting means, and means for shifting said molding device to alternately position its recesses for operation of said ejecting means on their compressed charges.

31. In can filling apparatus, a rotatable support, said support having a plurality of can seats, means on which said support is mounted for bodily movement, and means for shifting said support on said first means comprising companion thrust cams one of which is supported for relative rotation. 45

Signed at Seattle, Wash. this 24 day of December 1910.
